(57) **CLAIM**

The ornamental design for an arthroplasty prosthesis, as shown and described.

DESCRIPTION

FIG. 1 is a perspective view of an arthroplasty prosthesis according to a first embodiment.

FIG. 2 is a rear view of an arthroplasty prosthesis according to the embodiment of FIG. 1.

FIG. 3 is a front view of an arthroplasty prosthesis according to the embodiment of FIG. 1.

FIG. 4 is a left side view of an arthroplasty prosthesis according to the embodiment of FIG. 1.

FIG. 5 is a right side view of an arthroplasty prosthesis according to the embodiment of FIG. 1.

FIG. 6 is a top view of an arthroplasty prosthesis according to the embodiment of FIG. 1.

FIG. 7 is a bottom view of an arthroplasty prosthesis according to the embodiment of FIG. 1.

FIG. 8 is a perspective view of an arthroplasty prosthesis according to a second embodiment.

FIG. 9 is a rear view of an arthroplasty prosthesis according to the embodiment of FIG. 2.

FIG. 10 is a front view of an arthroplasty prosthesis according to the embodiment of FIG. 2.

FIG. 11 is a left side view of an arthroplasty prosthesis according to the embodiment of FIG. 2.

FIG. 12 is a right side view of an arthroplasty prosthesis according to the embodiment of FIG. 2.

FIG. 13 is a top view of an arthroplasty prosthesis according to the embodiment of FIG. 2.

FIG. 14 is a bottom view of an arthroplasty prosthesis according to the embodiment of FIG. 2.

FIG. 15 is a perspective view of an arthroplasty prosthesis according to a third embodiment.

FIG. 16 is a rear view of an arthroplasty prosthesis according to the embodiment of FIG. 3.

FIG. 17 is a front view of an arthroplasty prosthesis according to the embodiment of FIG. 3.

FIG. 18 is a left side view of an arthroplasty prosthesis according to the embodiment of FIG. 3.

FIG. 19 is a right side view of an arthroplasty prosthesis according to the embodiment of FIG. 3.

(Continued)

FIG. 20 is a top view of an arthroplasty prosthesis according to the embodiment of FIG. 3; and, FIG. 21 is a bottom view of an arthroplasty prosthesis according to the embodiment of FIG. 3.

The dash-dash broken lines shown in the figures represent portions of the arthroplasty prosthesis that form no part of the claimed design. The dot-dash broken lines shown in the figures define the bounds of the claimed design and form no part thereof.
